(57) **CLAIM**

The ornamental design for a belt hook, as shown and described.

DESCRIPTION

FIG. 1 is a perspective view of the belt hook.

FIG. 2 is a front elevational view of the belt hook of FIG. 1.

FIG. 3 is a rear elevational view of the belt hook of FIG. 1.

FIG. 4 is a top plan view of the belt hook of FIG. 1.

FIG. 5 is a bottom plan view of the belt hook of FIG. 1; and, FIG. 6 is a side elevational view of the belt hook of FIG. 1, the opposite side being a mirror image thereof.
